REFRIGERATION CONTROL SYSTEM

Alwin B. Newton, Minneapolis, Minn., assignor to
Minneapolis-Honeywell Regulator Company,
Minneapolis, Minn., a corporation of Delaware

Application July 24, 1939, Serial No. 286,053

24 Claims. (Cl. 62—4)

This invention relates to a control system for a refrigerating apparatus having evaporator means for controlling the condition of a medium and a mechanism for controlling the circulation of refrigerant through the evaporator means.

An object of this invention is to provide an automatic control system responsive to a condition which is a measure of evaporator temperature, such as suction pressure, and responsive to the condition of the medium being controlled by the evaporator means, such as space temperature, for controlling the mechanism to start circulation of refrigerant through the evaporator means only when the evaporator temperature increases to a predetermined high value, to continue circulation of refrigerant through the evaporator means when the condition of the medium is below a desired value until the evaporator temperature decreases to a predetermined value, or to continue circulation of refrigerant through the evaporator means as long as the condition of the medium is above the desired value even though the evaporator temperature should decrease below this predetermined value.

Another object of this invention is to provide the above control system with a means responsive to the pressure on the high pressure side of the refrigerating apparatus for stopping circulation of refrigerant through the evaporator means if the pressure should rise to a predetermined high value. Provision may also be made for preventing starting of the refrigerating apparatus until the pressure on the high pressure side decreases to a predetermined low value and this also forms another object of this invention.

Still another object of this invention is to stop operation of the refrigerating apparatus if the evaporator temperature or suction pressure should decrease to a predetermined low value.

Further objects of this invention are directed to the construction and mode of operation of electrical and mechanical control arrangements for obtaining the above sequences of operation.

Other objects and advantages will become apparent to those skilled in the art upon reference to the accompanying specification, claims and drawings, in which:

Figure 1 is a diagrammatic illustration of one form of this invention;

Figure 2 is a diagrammatic illustration of another form of this invention;

Figure 3 is a diagrammatic illustration of still another form of this invention for accomplishing mechanically substantially that which is accomplished electrically in Figures 1 and 2;

Figure 4 is a view similar to Figure 3 showing the parts in different positions; and

Figures 5 and 6 are diagrammatic illustrations of further modified forms of the invention

similar to the construction of the form illustrated in Figures 3 and 4.

Referring now to Figure 1 the refrigerating system is shown to be applied to an enclosure 10 for cooling the same. The enclosure 10 may be a storage compartment, counter-case, water cooler, walk-in box, or other space which it is desired to cool. The enclosure 10 is cooled by a cooling coil which may take the form of an evaporator 11 and refrigerant is circulated through the evaporator 11 by means of a refrigerating apparatus generally designated at 12. The refrigerating apparatus 12 may comprise a compressor 13 driven by an electric motor 14 for discharging compressed refrigerant through a high pressure line 15 into a condenser 16. Condensed refrigerant is collected in a receiver 17 and is discharged through a liquid line 18 to the evaporator 11. Evaporated refrigerant is withdrawn from the evaporator 11 through a suction line 19 by the compressor 13. The flow of refrigerant to the evaporator 11 may be controlled by a thermostatic expansion valve 20 having a thermal bulb 21 responding to the temperature of the refrigerant leaving the evaporator 11. The above outlined construction is conventional in the art and therefore a further description thereof is not considered necessary, it being sufficient to state that when the compressor 13 is placed in operation the evaporator 11 performs a cooling function for cooling the enclosure 10.

The compressor motor 14 and hence the compressor 13 is controlled by a relay or starter generally designated at 23 and this relay or starter is in turn controlled by a controller 24 responsive to a condition which is a measure of evaporator temperature such as suction pressure, by a controller 25 responsive to the pressure on the high pressure side of the refrigerating apparatus, and by a controller 26 responsive to a condition being controlled by the evaporator 11 such as temperature within the enclosure 10.

The relay or starter 23 may include an operating coil 28 for operating switch arms 29 and 30 with respect to contacts 31 and 32. When the operating coil 28 is energized the switch arms 29 and 30 are moved into engagement with their respective contacts 31 and 32 and when the operating coil 28 is deenergized the switch arms are moved out of engagement with their respective contacts by means of springs, gravity or other means, not shown.

The controller 24 responsive to a condition indicative of evaporator temperature such as suction pressure may comprise a bellows 34 connected by a pipe 35 to the suction line 19. The bellows 34 operates a lever 36 against the action of an adjustable tension spring 37 for operating a mercury switch 38. For purposes of illustration

it is assumed that when the suction pressure increases to 33 lbs. the switch 38 is closed and when the suction pressure decreases to 27 lbs. the switch 38 is opened. For purposes of illustration it is also assumed that the suction pressure value of 33 lbs. is a defrosting value so that the switch 38 may be closed only after the evaporator 11 has defrosted. In this respect the switch 38 might also be operated thermostatically by a bulb responding to the evaporator temperature directly instead of being operated in accordance with changes in suction pressure as illustrated here.

The controller 25 responsive to the pressure on the high pressure side of the refrigerating apparatus may comprise a bellows 40 connected by a pipe 41 to the high pressure line 15. The bellows 40 operates a lever 42 against the action of an adjustable tension spring 43 for operating a mercury switch 44. For purposes of illustration it is assumed that the mercury switch 44 is moved to an open position when the head pressure or pressures on the high pressure side of the refrigerating apparatus increases to 180 lbs. and is moved to a closed position when the head pressure decreases to 170 lbs.

The controller 26 responsive to a condition controlled by the evaporator 11, such as the temperature within the enclosure 10, may comprise a bellows 46 connected by a capillary tube 47 to a bulb 48 located within the enclosure 10. The bulb 48 is preferably charged with a volatile fluid so that the bellows 46 is expanded and contracted in accordance with changes in temperature within the enclosure 10. The bellows 46 operates a lever 49 against the action of an adjustable tension spring 50 for operating a mercury switch 51. For purposes of illustration it is assumed that when the temperature within the enclosure 10 increases to 41° the mercury switch 51 is closed and when the temperature decreases to 40° the mercury switch 51 is open. While the controller 26 is shown for purposes of illustration as responding to dry bulb temperature within the enclosure 10, the controller might also respond to the wet bulb temperature or the relative humidity within the enclosure 10 and still remain within the contemplation of this invention.

Power is supplied to the control system and to the electric motor 14 for driving the compressor 13 by means of line wires 230 and 231 leading from some source of power, not shown.

Assume now that the pressure on the high pressure side of the refrigerating apparatus is below 180 lbs. so that the mercury switch 44 is closed and that the temperature within the enclosure 10 is below 41° so that the mercury switch 51 is open. Also assume that the refrigerating apparatus is stopped and that the suction pressure is increasing. When the evaporator 11 has defrosted and the suction pressure has risen to 33 lbs., the mercury switch 38 is closed to complete a circuit from the line wire 230 through wire 232, mercury switch 38, wire 233, operating coil 28 and wire 234 back to the other line wire 231. Completion of this circuit energizes the operating coil 28 to move the switch arms 29 and 30 into engagement with their respective contacts 31 and 32. Movement of the switch arm 30 into engagement with the contact 32 completes a load circuit for the compressor motor 14 which may be traced from the line wire 230 through wire 235, switch arm 30, contact 32, wire 236, compressor motor 14 and wire 237 back to the other line wire 231. Hence, when the suction pressure increases to 33

lbs. the compressor 13 is started to circulate refrigerant through the evaporator 11 and the compressor 13 will remain in operation until such time as the suction pressure decreases to 27 lbs. 5 to open the mercury switch 38. The compressor motor 14 and hence the compressor 13 are therefore cycled on and off by the suction pressure controller 24 to maintain the evaporator 11 relatively cool to assist in the circulation of air throughout the enclosure 10. After the compressor is shut down it cannot again be restarted until such time as the evaporator 11 has defrosted.

Assume now that the temperature within the enclosure 10 rises to 41° to close the mercury switch 51. However, no circuits are completed immediately upon closure of the mercury switch 51 since the circuit through the mercury switch 51 also passes through the switch arm 29 and contact 31 of the relay or starter 23. When the suction pressure increases to 33 lbs. to start the compressor 13 in the manner pointed out above the switch arm 29 of the relay or starter 23 engages the contact 31 and if at this time the mercury switch 51 of the temperature responsive controller 26 is calling for operation of the compressor, a circuit is then completed from the line wire 230 through wire 232, wire 240, mercury switch 44, wire 241, mercury switch 51, wire 242, contact 31, switch arm 29, wire 243, operating coil 28 and wire 234 back to the other line wire 231. Completion of this circuit maintains the relay or starter 23 pulled in and hence the compressor 13 in operation until such time as the temperature within the enclosure 10 decreases to 40° to open the mercury switch 51 regardless of whether the suction pressure decreases below 27 lbs. Thus after the compressor is placed in operation by the suction pressure controller 24 it will remain in operation until such time as the temperature within the enclosure 10 decreases to 40° to open the mercury switch 51 of the temperature responsive controller 26. Desired temperature conditions are therefore at all times maintained within the enclosure 10.

It is here noted that the controller 25 responsive to the pressure on the high pressure side of the refrigerating apparatus is located in series with the temperature responsive controller 26 so that if the pressure on the high pressure side of the refrigerating apparatus should become excessive, as illustrated over 180 lbs., then the last mentioned circuit is interrupted and the relay or starter 23 is dropped out to stop operation of the compressor 13. The compressor 13 cannot again be restarted until such time as the suction pressure increases to 33 lbs. to close the mercury switch 38.

The operation of Figure 1 may be summarized briefly as follows. The refrigerating apparatus is cyclically operated by the suction pressure controller 24 and the compressor cannot be started until such time as the suction pressure increases to a value indicating that the evaporator 11 has defrosted. If when the compressor is started by the suction pressure controller 24 the temperature responsive controller 26 is calling for cooling, the refrigerating apparatus will be maintained in operation until such time as the temperature responsive controller 26 is satisfied. In this way desired temperature conditions are maintained within the enclosure 10. Since the temperature responsive controller 26 cannot itself start the refrigerating apparatus 70 in operation it is impossible therefore to start

the refrigerating apparatus until such time as the evaporator 11 has defrosted. If during the operation of the compressor the pressure on the high pressure side of the refrigerating apparatus should become excessive then the refrigerating apparatus is stopped and cannot again be restarted until the evaporator 11 has defrosted.

Figure 2 illustrates a different arrangement for accomplishing substantially the same results as are accomplished in Figure 1. In Figure 2 the compressor motor and hence the compressor are controlled by a unitary control arrangement generally designated at 55 which may be of the type shown and described in application Serial No. 196,447 filed by Albert L. Judson and Carl G. Kronmiller on March 17, 1938. For purposes of illustration in this application the unitary control arrangement 55 is shown to include a control device 56 responsive to a condition which is a measure of evaporator temperature such as suction pressure, a control device 57 responsive to head pressure, that is the pressure on the high pressure side of the refrigerating apparatus, an overload cut-out 58 and a relay or starter 59. The compressor motor and hence the compressor are also controlled by a controller 60 responsive to a condition controlled by the evaporator such as compartment temperature and if desired by a second controller 61 responsive to a condition which is a measure of evaporator temperature such as suction pressure.

The control device 56 of the unitary control arrangement 55 responsive to changes in suction pressure may comprise a bellows 63 connected by a pipe 64 to the suction pressure line of the refrigerating apparatus for operating a lever 65 pivoted on a fulcrum member 66 against the action of an adjustable tension spring 67. One end of the tension spring 67 is connected to the lever 65 and the other end is connected to an adjusting screw arrangement 68. The lever 65 carries an insulating pad 69 which in turn carries a bridge member 70. A contact 71 carried by the bridge member 70 is adapted to engage a contact member 72 carried by a terminal 73. A second contact 74 carried by the bridge member 70 is adapted to engage a contact member 75 carried by a terminal 76. A pair of concentrically arranged cams 77 and 78 are utilized for independently adjusting the position of the contact members 72 and 75 with respect to their contacts 71 and 74. For purposes of illustration it is assumed that the parts are so arranged that upon an increase in suction pressure the contact 71 first engages the contact member 72 at 27 lbs. and then the contact 74 engages the contact member 75 at 33 lbs. Conversely upon a decrease in suction pressure the contact 74 first disengages the contact member 75 at 33 lbs. and then the contact 71 disengages the contact member 72 at 27 lbs.

The control device 57 of the unitary control arrangement 55 responsive to changes in head pressure may comprise a bellows 80 connected by a pipe 81 to the high pressure line of the refrigerating apparatus. The bellows 80 operates a lever 82 fulcrumed on a fulcrum member 83 against the action of an adjustable tension spring 84. One end of the tension spring 84 is connected to the lever 82 and the other end is connected to an adjusting screw arrangement 85. The lever 82 adjustably carries an abutment member 86 formed of insulating material and having abutment surfaces 87 and 88. The abutment surface 87 is adapted to engage a

contact member 89 carried by a terminal 90 to separate the contact member 89 from a contactor 91. The abutment surface 88 is adapted to engage a contact member 92 carried by the terminal 76 to move the contact member 92 out of engagement with a contact 93. For purposes of illustration it is assumed that upon an increase in pressure on the high pressure side of the refrigerating apparatus the contact member 92 is first moved out of engagement with the contact 93 at 140 lbs. and then the contact member 89 is moved out of engagement with the contact 91 at 180 lbs. Conversely upon a decrease in head pressure the contact member 89 first engages the contact 91 at 180 lbs. and then the contact member 92 engages the contact 93 at 140 lbs.

The overload cut-out device 58 may comprise a housing 94 to which is secured a terminal 95 and a contact 96. A heater element 97 is connected across the terminal 95 and the contact 96 for heating a thermostatic element enclosed within the housing 94. When the current flow through the heater element 97 becomes excessive the thermostatic element, not shown, trips a latch to separate control contacts 98 and 99. The control contacts 98 and 99 may be manually reclosed by a manual reset lever 100.

The relay or starter 59 may comprise an operating coil 102 for operating bridge members 103 and 106. When the operating coil 102 is energized the bridge member 103 is moved into engagement with contacts 104 and 105 and the bridge member 106 is moved into engagement with contacts 96 and 107. When the operating coil 102 is deenergized the bridge members 103 and 106 are moved out of engagement with their respective contacts by means of springs, gravity or other means, not shown. The unitary control arrangement 55 also includes a control terminal 108 connected by a wire 147 to the contact 104 and a load terminal 109.

The controller 60 responsive to the condition being controlled by the evaporator, such as enclosure temperature, may comprise a bellows 111 connected by a capillary tube 112 to a bulb 113 which may be located in the enclosure to be cooled. The bulb 113 is charged with a volatile fluid so that the bellows 111 is expanded and contracted in accordance with changes in temperature. The bellows 111 operates a lever 114 against the action of an adjustable tension spring 115 for operating a mercury switch 116. For purposes of illustration it is assumed that when the temperature affecting the bulb 113 increases to 41° the mercury switch 116 is closed and when the temperature decreases to 40° the mercury switch 116 is opened.

The controller 61 responsive to a condition indicative of evaporator temperature such as suction pressure may comprise a bellows 118 connected by a pipe 119 to the suction line of the refrigerating apparatus. The bellows 118 operates a lever 120 against the action of an adjustable tension spring 121 to operate a mercury switch 122. For purposes of illustration it is assumed that when the suction pressure decreases to 15 lbs. the mercury switch 122 is opened and when the suction pressure rises to 18 lbs. the mercury switch 122 is reclosed. However, as far as the sequence of operation is concerned the mercury switch 122 may be reclosed at any suction pressure value up to 33 lbs. which is the value at which the contact 74 of the unitary control arrangement 55 engages the contact mem-

ber 75. All that is necessary is that the mercury switch 122 opens when the suction pressure decreases to 15 lbs. and is reclosed by the time the suction pressure rises to 33 lbs.

A manual switch generally designated at 123 may comprise a switch arm 124 adapted to engage contacts 125 and 126. If it be desired to connect the suction pressure controller 61 into the control circuit the switch arm 124 is moved into engagement with the contact 125 and if it be desired to eliminate the suction pressure controller 61 from the control circuit the switch arm 124 is moved into engagement with the contact 126. If it be desired to eliminate the temperature control feature from the system, then the manual switch 124 may be positioned as shown in Figure 2.

Power is supplied to the control system and to the compressor motor by means of line wires 128 and 129 leading from some source of power, not shown.

Assume now that the temperature within the enclosure is below 41° so that the mercury switch 116 of the temperature responsive controller 60 is opened, that the switch arm 124 of the manual switch 123 is engaging the contact 125 so that the suction pressure responsive controller 61 is included in the system, that the suction pressure increases to 33 lbs. to cause the contacts 71 and 74 to engage the contact members 72 and 75 and that the head pressure decreases to 140 lbs. to cause the contact members 89 and 92 to engage the contacts 91 and 93. Under these conditions a starting circuit for the relay or starter 59 is completed and this starting circuit may be traced from the line wire 128 through contact 91, contact member 89, terminal 90, conductor 130, terminal 73, contact member 72, contact 71, bridge member 78, contact 74, contact members 75 and 92, contact 93, conductor 131, contact 105, conductor 132, control contacts 98 and 99, conductor 133, operating coil 102, conductor 134 and terminal 109 back to the other line wire 129. Completion of this circuit energizes the operating coil 102 to move the bridge members 103 and 106 into engagement with their respective contacts.

Movement of the bridge member 106 into engagement with the contacts 98 and 107 completes a load circuit which may be traced from the line wire 128 through contact 91, wire 136, terminal 95, heater element 97, contact 96, bridge member 108, contact 107, wire 137, the compressor motor, wire 138, and terminal 109 back to the other line wire 129. Thus when the suction pressure increases to 33 lbs. the compressor motor and hence the compressor is placed in operation.

Movement of the bridge member 103 into engagement with the contacts 104 and 105 completes a first maintaining circuit for the operating coil 59 which may be traced from the line wire 128 through contact 91, contact member 89, terminal 90, conductor 130, terminal 73, contact member 72, contact 71, bridge member 78, conductor 140, contact 104, bridge member 103, contact 105, conductor 132, control contacts 98 and 99, conductor 133, operating coil 102, conductor 134, and terminal 109 back to the other line wire 129. Completion of this circuit maintains the compressor motor and hence the refrigerating apparatus in operation until either the suction pressure decreases to 27 lbs. to move the contact member 72 out of engagement with the contact 71 or until the pressure on the high pressure side of the refrigerating apparatus increases to 180

lbs. to move the contact member 89 out of engagement with the contact 91. Accordingly when both the suction pressure increases to a predetermined high value, illustratively 33 lbs., and the pressure on the high pressure side decreases to a predetermined low value, illustratively 140 lbs., the compressor of the refrigerating apparatus is started and the compressor remains in operation until either the suction pressure decreases to an intermediate value of illustratively 27 lbs., or the head pressure increases to a high value of 180 lbs.

Assume now that the temperature within the enclosure increases to 41° to close the mercury switch 116 of the temperature responsive controller 60. Here as in the modification of Figure 1 this alone cannot start operation of the compressor. Under these conditions when the suction pressure increases to 33 lbs. and the head pressure decreases to 140 lbs. to pull in the relay or starter 59, a second maintaining circuit is completed from the line wire 128, through contact 91, contact member 89, terminal 90, conductor 130, terminal 73, wire 142, mercury switch 116, wire 143, switch arm 124, contact 125, wire 144, mercury switch 122, wire 145, contact 126, wire 146, terminal 108, conductor 147, contact 104, bridge member 103, contact 105, conductor 132, control contacts 98 and 99, conductor 133, operating coil 102, conductor 134, and terminal 109 back to the other line wire 129. Completion of this circuit maintains the relay or starter 59 pulled in and hence the compressor in operation until either the temperature within the compartment decreases to 40° to open the mercury switch 116 or the pressure on the high pressure side of the refrigerant apparatus increases to 180 lbs. to move the contact member 89 out of engagement with the contact 91. It is also noted that the mercury switch 122 of the suction pressure responsive controller 61 is included in series in this second maintaining circuit so that if the suction pressure decreases to 15 lbs. to open the mercury switch 122 the relay or starter 59 is also dropped out to stop operation of the compressor. After the compressor has been stopped by the occurrence of either of these three conditions it cannot again be restarted until such time as the suction pressure increases to 33 lbs. and the head pressure decreases to 140 lbs.

The operation of Figure 2 may be summarized briefly as follows. When the temperature responsive controller 60 is satisfied the compressor is started when the suction pressure rises to a predetermined value, illustratively 33 lbs., and the head pressure decreases to a predetermined value, illustratively 140 lbs., and is maintained in operation until either the suction pressure decreases to an intermediate value, illustratively 27 lbs., or the head pressure increases to a high value, illustratively 180 lbs. In this way the compressor is intermittently operated in accordance with changes in suction pressure or evaporator temperature. If when the compressor is started as outlined above the temperature within the compartment rises to a predetermined value, illustratively 41°, the compressor is maintained in operation until either the temperature within the compartment decreases to a predetermined value, illustratively 40°, or the suction pressure decreases to a predetermined low value, illustratively 15 lbs., or until the head pressure increases to a predetermined high value, illustratively 180 lbs. In this way desired temperature conditions are at all times maintained within the enclosure.

Referring now to Figures 3 and 4, there is disclosed a mechanical arrangement for accomplishing substantially the same results as are accomplished by the electrical arrangement of Figure 2. Here a single control arrangement is generally designated at 150 and is provided with a control device 151 responsive to a condition which is a measure of evaporator temperature such as suction pressure, a control device 152 responsive to head pressure or pressure on the high pressure side of the refrigerating apparatus, and a control device 153 responsive to a condition controlled by the evaporator such as the temperature of the enclosure for operating a switching mechanism generally designated at 154.

The control device 151 responsive to a condition which is a measure of evaporator temperature such as suction pressure may comprise a bellows casing 156 in which is mounted a bellows for operating a plunger 157. The bellows casing 156 is connected by a pipe to the suction pressure line of the refrigerating apparatus. The plunger 157 is therefore operated in accordance with changes in suction pressure or evaporator temperature. The plunger 157 operates a lever 158 fulcrumed on a knife edge 159. The lever 158 is provided with an ear 160 to which is secured one end of an adjustable tension spring 161. The other end of the tension spring 161 is connected to a nut 162 screw-threadedly mounted on a screw 163. By rotating the screw 163 the tension of the spring 161 may be adjusted at will. A bracket 164 carries stops 165 and 166 for limiting movement of the pivoted lever 158. Upon an increase in suction pressure the lever 158 is moved in a counter-clockwise direction and upon a decrease in suction pressure the lever 158 is moved in a clockwise direction.

The lever 158 is provided with an extension 168 and an arm 169 is pivoted to the extension 168 by a pivot pin 170. The extension 168 is provided with a lug 171 which is normally engaged by the arm 169. The extension 168 is provided with another lug 172 and the arm 169 is provided with a lug 173, a spring 174 being connected between the lugs 172 and 173 to urge the arm 169 into engagement with the lug 171 as shown in Figure 3. The arm 169 therefore normally moves coextensively with the extension 168, the spring 174 providing a strain release the purpose of which will be pointed out more fully hereafter. The arm 169 carries a pin 175 for operating the switching mechanism 154.

The switching mechanism 154 may comprise a switch carrier 177 pivoted at 178 for carrying a mercury switch 179. The lower end of the carrier 177 is provided with two arms 180 and 181 to be engaged by the pin 175. When the pin 175 is moved to the left and engages the arm 180 to move the carrier 177, the mercury switch 179 is moved to a closed position and when the pin 175 moves to the right into engagement with the arm 181 to move the carrier 177, the mercury switch 179 is opened.

The temperature responsive controller 153 may comprise bellows 182 carried by a bracket 183. A capillary tube 184 connects the bellows 182 with a bulb 185 which may be located within the enclosure to be cooled. The bulb 185 may be charged with a volatile fluid so that the bellows 182 is expanded and contracted in accordance with changes in temperature. The bellows 182 operates a lever 186 pivoted at 187 to the bracket 164 and provided with a latch member 188. The lever 186 is urged in a counter-clock-

wise direction about the pivot 187 by means of an adjustable spring 190, one end of the spring 190 being connected to the lever 186 and the other end being connected to a nut 191 screw-threadedly mounted on a screw 192. By rotating the screw 192 the tension of the spring 190 may be adjusted at will. Upon an increase in temperature the lever 186 is moved in a clockwise direction and upon a decrease in temperature it is moved in a counter-clockwise direction. Stops 193 and 194 carried by the bracket 183 are utilized for limiting the amount of movement of the lever 186. For purposes of illustration it is assumed that when the temperature 15 within the compartment increases to 41° the lever 186 is moved against the lower stop 194 as illustrated in Figure 3 and when the temperature decreases to 40° the lever 186 is moved against the upper stop 193 as illustrated in Figure 4.

An arm 196 is pivoted to the bracket 164 by a pin 197 and carries an abutment surface 198 to be engaged by the lever 158. The arm 196 is urged in a counter-clockwise direction by an adjustable tension spring 199, one end of the spring 199 being connected to the arm 196 and the other end being connected to a nut 200 screw-threadedly mounted on a screw 201. By rotating the screw 201 the tension in the spring 199 may be adjusted at will. The latch member 188 carried by the lever 186 is adapted under certain conditions to limit the counter-clockwise movement of the arm 196 as is evidenced in Figure 3. However, when the latch member 188 is retracted as shown in Figure 4 the movement of the arm 196 by the spring 199 is not limited.

The control device 152 responsive to head pressure, that is, the pressure on the high pressure side of the refrigerating apparatus, may comprise a bellows casing 205 in which is mounted a bellows for operating a plunger 207. The bellows casing 205 is connected by a pipe to the high pressure line of the refrigerating apparatus so that the bellows within the casing 205 is expanded and contracted in accordance with changes in head pressure. A spring is also located within the bellows casing 205 for opposing the pressure therein and this spring may be adjusted by a suitable nut 206. The plunger 207 is adapted to engage one end of a lever 208 pivoted by a pin 209 to a bracket 210 and the other end of the lever 208 is adapted to engage a lug 211 carried by the arm 169.

Power is supplied to the compressor by means of line wires 213 and 214 leading from some source of power, not shown, and when the mercury switch 179 is closed a circuit is completed from the line wire 214 through the mercury switch 179, wire 215 and the compressor motor back to the other line wire 213 to cause operation of the compressor motor and hence operation of the refrigerating apparatus.

Omitting for the time being the operation of the head pressure responsive controller 152 let it be assumed that the parts are in the position shown in Figure 3. The mercury switch 179 is open and hence the compressor is not operating. The temperature within the compartment has increased to 41° to cause the latch member 188 to engage the arm 196. Since the compressor is not operating the suction pressure within the refrigerating apparatus is increasing to move the lever 158 in a counter-clockwise direction. When the lever 158 engages the abutment surface 198

of the arm 196 further counter-clockwise movement of the lever 158 is retarded by both tension springs 161 and 199. At this point let it be assumed that the suction pressure is 30 lbs. As the suction pressure increases from 30 lbs. to 33 lbs. the lever 158 is moved in a counter-clockwise direction against the action of both springs 161 and 199. When the pressure finally reaches 33 lbs. whereupon the lever 158 is moved into engagement with the lower stop 166, the pin 175 carried by the arm 169 closes the mercury switch 179 and the compressor is placed in operation. Immediately upon placing the compressor in operation the suction pressure starts to decrease and when the suction pressure decreases to 30 lbs. the lever 158 assumes the position shown in Figure 3. At this point the tension spring 199 becomes ineffective to move the lever 158 in a clockwise direction since the arm 196 is limited in its movement by the latch member 188. Accordingly only one spring 161 is then urging the lever 158 in a clockwise direction about the pivot 159. When the suction pressure decreases to 16 lbs. the lever 158 starts to move in a clockwise direction about the pivot 159 under the influence of the spring 161 and when the pressure finally decreases to 15 lbs. the lever 158 is moved into engagement with the upper stop 165 whereupon the pin 175 carried by the arm 169 opens the mercury switch 179. The compressor is then stopped and the suction pressure starts to rise. When the suction pressure rises from 15 lbs. to 16 lbs. the lever 158 moves from the upper stop 165 into engagement with the abutment surface 198 as shown in Figure 3. A further rise in suction pressure is then resisted by both springs 161 and 199 and the lever will not move from the position shown in Figure 3 toward the bottom stop until such time as the suction pressure starts rising above 30 lbs. Thus when the temperature within the enclosure is at 41° and calling for cooling the compressor is started only when the suction pressure increases to 33 lbs. and remains in operation until such time as the suction pressure decreases to 15 lbs.

If after the compressor has been started in the manner outlined immediately above and is operating to reduce the pressure on the low pressure side of the refrigerating apparatus the temperature responsive controller 153 should become satisfied before the suction pressure is decreased to 15 lbs. then the latch member 188 is moved out of engagement with the arm 196. If the suction pressure should be below for example 27 lbs. both springs 161 and 199 will become effective to move the lever 158 in a clockwise direction to the upper stop 165 to open the mercury switch 179 and the compressor will then be stopped.

Assume now that the temperature within the compartment is 40° whereupon the lever 186 is moved against the upper stop 193 and the latch member 188 is retracted. When the suction pressure increases to 33 lbs. both springs 161 and 199 are overcome and the lever 158 is moved against the lower stop 166 to close the mercury switch 179. The compressor is then placed in operation and the suction pressure is caused to decrease. As the suction pressure decreases from 33 lbs. the lever 158 moves in a clockwise direction under the influence of both springs 161 and 199 and when the suction pressure under these conditions decreases to 30 lbs. the parts will assume the position shown in Figure 4. Here it is noted that the latch member 188 is retracted so that both

springs 161 and 199 still tend to urge the lever 158 in a clockwise direction. When the suction pressure decreases to 27 lbs. the lever 158 is moved against the upper stop 165 by both springs 161 and 199 and the mercury switch 179 is opened. The compressor is then stopped and cannot be restarted until such time as the suction pressure rises to 33 lbs. to allow the lever 158 to engage the lower stop 166 to reclose the mercury switch 179.

Assume now that the parts are in the position shown in Figure 4 with the mercury switch 179 closed and the compressor in operation. If now the head pressure or the pressure on the high pressure side of the refrigerating apparatus should increase to a predetermined high value illustratively 180 lbs., the plunger 207 will engage the upper end of the lever 208 to move the lever 208 in a counter-clockwise direction. Counter-clockwise movement of the lever 208 will cause engagement with the lug 211 of the arm 169 to move the mercury switch 179 to the "off" position, this movement being permitted by the strain release connection afforded by the spring 174 located between the lugs 172 and 173. Thus when the pressure on the high pressure side of the refrigerating apparatus increases to a predetermined high value, namely 180 lbs., the mercury switch 179 is opened and the compressor is stopped. The compressor cannot be restarted until the lever 208 is retracted sufficiently to allow the mercury switch 179 to close and this will not occur until such time as the pressure on the high pressure side of the refrigerating apparatus decreases to 140 lbs. Further still, the mercury switch 179 cannot be moved to a closed position until such time as the suction pressure rises to 33 lbs. due to the differential action of the mercury switch 179 and the lost motion connection between the pin 175 and the arms 180 and 181.

Thus it will be seen that when the mercury switch 179 is opened either by the suction pressure controller 151 or the head pressure controller 152 it cannot again be reclosed until such time as the suction pressure rises to 33 lbs. or the head pressure decreases to 140 lbs.

The operation of the arrangement shown in Figures 3 and 4 may be summarized briefly as follows. When the temperature within the enclosure is below a predetermined value, illustratively 40°, the compressor may be started only when the suction pressure increases to 33 lbs. and the head pressure decreases to 140 lbs., and after the compressor is once started it will remain in operation until such time as either the suction pressure decreases to 27 lbs. or the head pressure increases to 180 lbs. Thus the refrigerating apparatus is intermittently operated by the suction pressure controller. The temperature responsive control device 153 is incapable in itself of starting operation of the refrigerating apparatus. If after the refrigerating apparatus is started by the suction pressure control device 151, the temperature responsive control device 153 should demand cooling upon an increase in enclosure temperature to 41° the compressor will be maintained in operation until either the temperature within the enclosure should decrease to a predetermined value, illustratively 40°, or the suction pressure should decrease to a predetermined low value, illustratively 15 lbs., or the pressure on the high pressure side of the refrigerating apparatus should increase to a predetermined high value, illustratively 180 lbs. Upon stopping of the compressor by the occurrence of any of these conditions it cannot be restarted until such

time as the suction pressure rises to 33 lbs. and the head pressure decreases to 140 lbs.

Referring now to Figure 5, the same control arrangement 150 is utilized as in Figure 3, the only difference being that a different temperature responsive control means 252 is utilized in place of the temperature responsive control means 153 of Figure 3. Accordingly, in Figures 3 and 5 like reference characters are utilized for like parts. The temperature responsive control means 252 of Figure 5 may comprise an electrical operating coil 253 carried by a bracket 254, the bracket 254 being provided with upper and lower stops 255 and 256. The lever 186 which operates the latch member 188 is provided with an upwardly extending extension 257 carrying an armature 258 to be influenced by the coil 253. When the operating coil 253 is energized the latch member 188 engages the lever 196 and when the operating coil 253 is deenergized the latch member 188 is retracted from the lever 196 by the tension spring 190.

The operating coil 253 is controlled by a thermostat generally designated at 260 which is responsive to the temperature within the space or enclosure to be controlled. The thermostat 260 may comprise a bellows 261 charged with a volatile fluid for operating a lever 262 against the action of an adjustable tension spring 263 for operating a mercury switch 264. For purposes of illustration it is assumed that when the temperature of the bellows 261 rises to 41° the mercury switch 264 is closed and when the temperature decreases to 40° the mercury switch 264 is opened.

Power is supplied to the operating coil 253 by means of wires 265 and 266 connected across wires 213 and 215, the operating coil 253 thereby being connected in parallel with the compressor motor. When the temperature condition affecting the thermostat 260 rises to 41° to close the mercury switch 264 and when the mercury switch 179 is closed, a circuit is completed from the line wire 214 through mercury switch 179, wires 215 and 265, mercury switch 264, wire 261, operating coil 253, and wire 266 back to the other line wire 213 to cause energization of the operating coil 253. When the operating coil 253 is energized the latch member 188 engages the lever 196 and the control arrangement of Figure 5 operates in exactly the same way as the control arrangement of Figure 3. When the temperature affecting the bellows 261 decreases to 40° the circuit through the operating coil 253 is broken and the latch member 188 disengages the lever 196 to cause the control arrangement of Figure 5 to operate in the same manner as the control arrangement of Figure 3. Accordingly, a more thorough description of the operation of the control arrangement of Figure 5 is not considered necessary. Since the operating circuit for the operating coil 253 passes through the mercury switch 179, the operating coil 253 is not called upon to operate the latch member 188 until the lever 196 is moved to the lower position to allow free movement of the latch member 188. Thus the operating coil 253 may be made smaller.

Referring now to Figure 6, the control arrangement 150 is exactly the same as that of Figure 3 with the exception that a different temperature responsive control means 273 is substituted for the temperature responsive control means 153 of Figure 3. In Figure 6 a pneumatic bellows 274 carried by a bracket 275 is

utilized for operating the lever 186 for in turn operating the latch member 188. The bracket 275 is provided with upper and lower stops 276 and 277 for limiting the movement of the lever 186. The pneumatic bellows 274 is connected by a branch line 278 to a pneumatic thermostat 279 responsive to the temperature of the medium being controlled. Air under pressure is supplied to the pneumatic thermostat 279 by an air supply pipe 280. When the temperature within the space being controlled rises to 41° the pneumatic thermostat 279 supplies air through the pipe 278 to the bellows 274 to cause the latch member 188 to engage the lever 186. When the temperature decreases to 40° the pneumatic thermostat 279 vents the air from the bellows 274 through the branch line 278 to allow the lever 186 to move against the upper stop 276 to release the latch member 188 from the lever 196. Accordingly the modification shown in Figure 6 operates in exactly the same manner as the modification shown in Figure 3 and therefore a more complete description of this modification is not considered necessary.

Although for purposes of illustration several forms of this invention have been disclosed, other forms thereof may become apparent to those skilled in the art upon reference to this disclosure and therefore this invention is to be limited only by the scope of the appended claims.

I claim as my invention:

1. In a refrigerating apparatus having evaporator means for controlling the condition of a medium and a mechanism for controlling the circulation of refrigerant through the evaporator means, the combination of, control means responsive to a condition which is a measure of evaporator temperature, control means responsive to the condition of the medium controlled by the evaporator means, and means controlled by both control means for controlling the mechanism to start circulation of refrigerant through the evaporator means only when the evaporator temperature increases to a predetermined high value, to continue circulation of refrigerant through the evaporator means when the condition of the medium controlled by the evaporator means is below a predetermined value until the evaporator temperature decreases to a predetermined low value or to continue circulation of refrigerant through the evaporator means as long as the condition of the medium controlled by the evaporator means is above said predetermined value regardless of whether the evaporator temperature decreases below the predetermined low value.

2. In a refrigerating apparatus having evaporator means for controlling the condition of a medium and a mechanism for controlling the circulation of refrigerant through the evaporator means, the combination of, first control means responsive to a condition which is a measure of evaporator temperature for controlling the mechanism to start circulation of refrigerant through the evaporator means only when the evaporator temperature rises to a predetermined high value and to stop circulation of refrigerant through the evaporator means when the evaporator temperature decreases to a predetermined low value, and second control means responsive to the condition of the medium controlled by the evaporator means for also controlling the mechanism when the condition rises to a predetermined value to maintain circulation of refrigerant through

the evaporator means after circulation has been started by the first control means regardless of whether the evaporator temperature decreases below the predetermined low value, said second control means being incapable of controlling said mechanism to start circulation of refrigerant through the evaporator means.

3. In a refrigerating apparatus having evaporator means for controlling the condition of a medium and a mechanism for controlling the circulation of refrigerant through the evaporator means, the combination of, control means responsive to a condition which is a measure of evaporator temperature, control means responsive to the condition of the medium controlled by the evaporator means, and means controlled by both control means for controlling the mechanism to start circulation of refrigerant through the evaporator means only when the evaporator temperature increases to a predetermined high value, to continue circulation of refrigerant through the evaporator means when the condition of the medium controlled by the evaporator means is below a predetermined value until the evaporator temperature decreases to a predetermined intermediate value or to continue circulation of refrigerant through the evaporator means as long as the condition of the medium controlled by the evaporator means is above said predetermined value provided the evaporator temperature does not decrease to a predetermined low value.

4. In a refrigerating apparatus having evaporator means for controlling the condition of a medium and a mechanism for controlling the circulation of refrigerant through the evaporator means, the combination of, control means responsive to a condition which is a measure of evaporator temperature, control means responsive to the condition of the medium controlled by the evaporator means, means controlled by both control means for controlling the mechanism to start circulation of refrigerant through the evaporator means only when the evaporator temperature increases to a predetermined high value, to continue circulation of refrigerant through the evaporator means when the condition of the medium controlled by the evaporator means is below a predetermined value until the evaporator temperature decreases to a predetermined low value or to continue circulation of refrigerant through the evaporator means as long as the condition of the medium controlled by the evaporator means is above said predetermined value regardless of whether the evaporator temperature decreases below the predetermined low value, and control means responsive to the pressure on the high pressure side of the refrigerating apparatus for controlling said mechanism to stop circulation of refrigerant through the evaporator means when the pressure increases to a predetermined high value.

5. In a refrigerating apparatus having evaporator means for controlling the condition of a medium and a mechanism for controlling the circulation of refrigerant through the evaporator means, the combination of, first control means responsive to a condition which is a measure of evaporator temperature for controlling the mechanism to start circulation of refrigerant through the evaporator means only when the evaporator temperature rises to a predetermined high value and to stop circulation of refrigerant through the evaporator means when the evaporator temperature decreases to a predetermined low value, second control means responsive to the condition of

the medium controlled by the evaporator means for also controlling the mechanism when the condition rises to a predetermined value to maintain circulation of refrigerant through the evaporator means after circulation has been started by the first control means regardless of whether the evaporator temperature decreases below the predetermined low value, said second control means being incapable of controlling said mechanism to start circulation of refrigerant through the evaporator means, and third control means responsive to the pressure on the high pressure side of the refrigerating apparatus for controlling said mechanism to stop circulation of refrigerant through the evaporator means when the pressure increases to a predetermined high value.

6. In a refrigerating apparatus having evaporator means for controlling the condition of a medium and a mechanism for controlling the circulation of refrigerant through the evaporator means, the combination of, control means responsive to a condition which is a measure of evaporator temperature, control means responsive to the condition of the medium controlled by the evaporator means, means controlled by both control means for controlling the mechanism to start circulation of refrigerant through the evaporator means only when the evaporator temperature increases to a predetermined high value, to continue circulation of refrigerant through the evaporator means when the condition of the medium controlled by the evaporator means is below a predetermined value until the evaporator temperature decreases to a predetermined intermediate value or to continue circulation of refrigerant through the evaporator means as long as the condition of the medium controlled by the evaporator means is above said predetermined value provided the evaporator temperature does not decrease to a predetermined low value, and control means responsive to the pressure on the high pressure side of the refrigerating apparatus for controlling said mechanism to stop circulation of refrigerant through the evaporator means when the pressure increases to a predetermined high value.

7. In a refrigerating apparatus having evaporator means for controlling the condition of a medium and a mechanism for controlling the circulation of refrigerant through the evaporator means, the combination of, control means responsive to a condition which is a measure of evaporator temperature, control means responsive to the condition of the medium controlled by the evaporator means, control means responsive to the pressure on the high pressure side of the refrigerating apparatus, and means controlled by all of the control means for controlling the mechanism to start circulation of refrigerant through the evaporator means only when the evaporator temperature increases to a predetermined high value and the pressure on the high pressure side decreases to a predetermined low value, to continue circulation of refrigerant through the evaporator means when the condition of the medium controlled by the evaporator means is below a predetermined value until either the evaporator temperature decreases to a predetermined low value or the pressure on the high pressure side increases to a predetermined high value or to continue circulation of refrigerant through the evaporator means as long as the condition of the medium controlled by the evaporator means is above said predetermined value un-

less the pressure on the high pressure side increases to said predetermined high value.

8. In a refrigerating apparatus having evaporator means for controlling the condition of a medium and a mechanism for controlling the circulation of refrigerant through the evaporator means, the combination of, control means responsive to a condition which is a measure of evaporator temperature, control means responsive to the condition of the medium controlled by the evaporator means, control means responsive to the pressure on the high pressure side of the refrigerating apparatus, and means controlled by all of the control means for controlling the mechanism to start circulation of refrigerant through the evaporator means only when the evaporator temperature increases to a predetermined high value and the pressure on the high pressure side decreases to a predetermined low value, to continue circulation of refrigerant through the evaporator means when the condition of the medium controlled by the evaporator means is below a predetermined value until either the evaporator temperature decreases to a predetermined intermediate value or the pressure on the high pressure side increases to a predetermined high value or to continue circulation of refrigerant through the evaporator means as long as the condition of the medium controlled by the evaporator means is above said predetermined value unless the pressure on the high pressure side increases to said predetermined high value or the temperature of the evaporator means decreases to a predetermined low value.

9. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second switch means, means responsive to a condition which is a measure of evaporator temperature for closing the second switch means when the evaporator temperature increases to a predetermined high value, means for completing a starting circuit through the second switch means independently of the first switch means to operate the electrically controlled mechanism to circulate refrigerant through the evaporator means, a maintaining switch, means for closing the maintaining switch as an incident to completion of the starting circuit, means for completing a maintaining circuit through the first switch means and the maintaining switch independently of the second switch means to maintain the electrically controlled mechanism in operation to circulate refrigerant through the evaporator means, said maintaining switch remaining closed as long as the maintaining circuit is completed.

10. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second switch means, means responsive to a condition which is a measure of evaporator temperature for closing the second switch

means when the evaporator temperature increases to a predetermined high value, third switch means, means responsive to the pressure on the high pressure side of the refrigerating apparatus for opening the third switch means when the pressure increases to a predetermined high value, means for completing a starting circuit through the second switch means independently of the first switch means to operate the electrically controlled mechanism to circulate refrigerant through the evaporator means, a maintaining switch, means for closing the maintaining switch as an incident to completion of the starting circuit, means for completing a maintaining circuit through the first switch means, the third switch means and the maintaining switch independently of the second switch means to maintain the electrically controlled mechanism in operation to circulate refrigerant through the evaporator means, said maintaining switch remaining closed as long as the maintaining circuit is completed.

11. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second and third switch means, means responsive to a condition which is a measure of evaporator temperature for closing the second switch means when the evaporator temperature increases to a predetermined high value and for opening the third switch means when the evaporator temperature decreases to a predetermined low value, means for completing a starting circuit through the second switch means independently of the first switch means to operate the electrically controlled mechanism to circulate refrigerant through the evaporator means, a maintaining switch, means for closing the maintaining switch as an incident to completion of the starting circuit, means for completing a maintaining circuit through the first and third switch means and the maintaining switch independently of the second switch means to maintain the electrically controlled mechanism in operation to circulate refrigerant through the evaporator means, said maintaining switch remaining closed as long as the maintaining circuit is completed.

12. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second and third switch means, means responsive to a condition which is a measure of evaporator temperature for closing the second switch means when the evaporator temperature increases to a predetermined high value and for opening the third switch means when the evaporator temperature decreases to a predetermined low value, means for completing a starting circuit through the second switch means independently of the first switch means to operate the electrically controlled mechanism to circulate refrigerant through the evaporator means, a maintaining switch, means for closing the maintaining switch as an incident to completion of

the starting circuit, means for completing a first maintaining circuit through the third switch means and the maintaining switch independently of the first and second switch means to maintain the electrically controlled mechanism in operation to circulate refrigerant through the evaporator means, and means for completing a second maintaining circuit through the first switch means and the maintaining switch independently of the second and third switch means to maintain the electrically controlled mechanism in operation to circulate refrigerant through the evaporator means, said maintaining switch remaining closed as long as either maintaining circuit is completed.

13. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second, third and fourth switch means, means responsive to a condition which is a measure of evaporator temperature for closing the second switch means when the evaporator temperature increases to a predetermined high value, for opening the third switch means when the evaporator temperature decreases to a predetermined intermediate value and for opening the fourth switch means when the evaporator temperature decreases to a predetermined low value, means for completing a starting circuit through the second switch means independently of the first switch means to operate the electrically controlled mechanism to circulate refrigerant through the evaporator means, a maintaining switch, means for closing the maintaining switch as an incident to completion of the starting circuit, means for completing a first maintaining circuit through the third switch means and the maintaining switch independently of the first and second switch means to maintain the electrically controlled mechanism in operation to circulate refrigerant through the evaporator means, and means for completing a second maintaining circuit through the first and fourth switch means and the maintaining switch independently of the second and third switch means to maintain the electrically controlled mechanism in operation to circulate refrigerant through the evaporator means, said maintaining switch remaining closed as long as either maintaining circuit is completed.

14. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second switch means, means responsive to a condition which is a measure of evaporator temperature for closing the second switch means when the evaporator temperature increases to a predetermined high value, third and fourth switch means, means responsive to the pressure on the high pressure side of the refrigerating apparatus for closing the third switch means when the pressure decreases to a predetermined low value and for opening the

fourth switch means when the pressure increases to a predetermined high value, means for completing a starting circuit through the second and third switch means independently of the first switch means to operate the electrically controlled mechanism to circulate refrigerant through the evaporator means, a maintaining switch, means for closing the maintaining switch as an incident to completion of the starting circuit, means for completing a maintaining circuit through the first and fourth switch means and the maintaining switch independently of the second and third switch means to maintain the electrically controlled mechanism in operation to circulate refrigerant through the evaporator means, said maintaining switch remaining closed as long as the maintaining circuit is completed.

15. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second and third switch means, means responsive to a condition which is a measure of evaporator temperature for closing the second switch means when the evaporator temperature increases to a predetermined high value, second and third switch means, means responsive to a condition which is a measure of evaporator temperature for closing the second switch means when the condition increases to a predetermined high value, for opening the third switch means when the evaporator temperature decreases to a predetermined low value, fourth switch means, means responsive to the pressure on the high pressure side of the refrigerating apparatus for opening the fourth switch means when the pressure increases to a predetermined high value, means for completing a starting circuit through the second switch means independently of the first switch means to operate the electrically controlled mechanism to circulate refrigerant through the evaporator means, a maintaining switch, means for closing the maintaining switch as an incident to completion of the starting circuit, means for completing a maintaining circuit through the first, third and fourth switch means and the maintaining switch independently of the second switch means to maintain the electrically controlled mechanism in operation to circulate refrigerant through the evaporator means, said maintaining switch remaining closed as long as the maintaining circuit is completed.

16. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second and third switch means, means responsive to a condition which is a measure of evaporator temperature for closing the second switch means when the evaporator temperature increases to a predetermined high value and for opening the third switch means when the evaporator temperature decreases to a predetermined low value, fourth switch means, means responsive to the pressure on the high pressure side of the refrigerating apparatus for opening the fourth switch means when the pressure increases to a predetermined high value, means for completing a starting circuit through

the second switch means independently of the first switch means to operate the electrically controlled mechanism to circulate refrigerant through the evaporator means, a maintaining switch, means for closing the maintaining switch as an incident to completion of the starting circuit, means for completing a first maintaining circuit through the third switch means and the maintaining switch independently of the first and second switch means to maintain the electrically controlled mechanism in operation to circulate refrigerant through the evaporator means, and means for completing a second maintaining circuit through the first and fourth switch means and the maintaining switch independently of the second and third switch means to maintain the electrically controlled mechanism in operation to circulate refrigerant through the evaporator means, said maintaining switch remaining closed as long as either maintaining circuit is completed.

17. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second, third and fourth switch means, means responsive to a condition which is a measure of evaporator temperature for closing the second switch means when the evaporator temperature increases to a predetermined high value, for opening the third switch means when the evaporator temperature decreases to a predetermined intermediate value and for opening the fourth switch means when the evaporator temperature decreases to a predetermined low value, fifth switch means, means responsive to the pressure on the high pressure side of the refrigerating apparatus for opening the fifth switch means when the pressure on the high pressure side increases to a predetermined high value, means for completing a starting circuit through the second switch means independently of the first switch means to operate the electrically controlled mechanism to circulate refrigerant through the evaporator means, a maintaining switch, means for closing the maintaining switch as an incident to completion of the starting circuit, means for completing a first maintaining circuit through the third switch means and the maintaining switch independently of the first and second switch means to maintain the electrically controlled mechanism in operation to circulate refrigerant through the evaporator means, and means for completing a second maintaining circuit through the first, fourth and fifth switch means and the maintaining switch independently of the second and third switch means to maintain the electrically controlled mechanism in operation to circulate refrigerant through the evaporator means, said maintaining switch remaining closed as long as either maintaining circuit is completed.

18. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means

when the condition increases to a predetermined high value, second and third switch means, means responsive to a condition which is a measure of evaporator temperature for closing the second switch means when the evaporator temperature increases to a predetermined high value and for opening the third switch means when the evaporator temperature decreases to a predetermined low value, fourth and fifth switch means, means responsive to the pressure on the high pressure side of the refrigerating apparatus for closing the fourth switch means when the pressure decreases to a predetermined low value and for opening the fifth switch means when the pressure increases to a predetermined high value, means for completing a starting circuit through the second and fourth switch means independently of the first switch means to operate the electrically controlled mechanism to circulate refrigerant through the evaporator means, a maintaining switch, means for closing the maintaining switch as an incident to completion of the starting circuit, means for completing a maintaining circuit through the first, third and fifth switch means and the maintaining switch independently of the second and fourth switch means to maintain the electrically controlled mechanism in operation to circulate refrigerant through the evaporator means, said maintaining switch remaining closed as long as the maintaining circuit is completed.

19. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second and third switch means, means responsive to a condition which is a measure of evaporator temperature for closing the second switch means when the evaporator temperature increases to a predetermined high value and for opening the third switch means when the evaporator temperature decreases to a predetermined low value, fourth and fifth switch means, means responsive to the pressure on the high pressure side of the refrigerating apparatus for closing the fourth switch means when the pressure decreases to a predetermined low value and for opening the fifth switch means when the pressure increases to a predetermined high value, means for completing a starting circuit through the second and fourth switch means independently of the first switch means to operate the electrically controlled mechanism to circulate refrigerant through the evaporator means, a maintaining switch, means for closing the maintaining switch as an incident to completion of the starting circuit, means for completing a first maintaining circuit through the third and fifth switch means and the maintaining switch independently of the first, second and fourth switch means to maintain the electrically controlled mechanism in operation to circulate refrigerant through the evaporator means, and means for completing a second maintaining circuit through the first and fifth switch means and the maintaining switch independently of the second, third and fourth switch means to maintain the electrically controlled mechanism in operation to circulate refrigerant through the evaporator means, said

maintaining switch remaining closed as long as either maintaining circuit is completed.

20. In a refrigerating apparatus having evaporator means for controlling the condition of a medium and an electrically controlled mechanism for controlling the circulation of refrigerant through the evaporator means, the combination of, first switch means, means responsive to the condition of the medium controlled by the evaporator means for closing the first switch means when the condition increases to a predetermined high value, second, third and fourth switch means, means responsive to a condition which is a measure of evaporator temperature for closing the second switch means when the evaporator temperature increases to a predetermined high value, for opening the third switch means when the evaporator temperature decreases to a predetermined intermediate value and for opening the fourth switch means when the evaporator temperature decreases to a predetermined low value, fifth and sixth switch means, means responsive to the pressure on the high pressure side of the refrigerating apparatus for closing the fifth switch means when the pressure decreases to a predetermined low value and for opening the sixth switch means when the pressure increases to a predetermined high value, means for completing a starting circuit through the second and fifth switch means independently of the first switch means to operate the electrically controlled mechanism to circulate refrigerant through the evaporator means, a maintaining switch, means for closing the maintaining switch as an incident to completion of the starting circuit, means for completing a first maintaining circuit through the third and sixth switch means and the maintaining switch independently of the first, second and fifth switch means to maintain the electrically controlled mechanism in operation to circulate refrigerant through the evaporator means, and means for completing a second maintaining circuit through the first, fourth and sixth switch means and the maintaining switch independently of the second, third and fifth switch means to maintain the electrically controlled mechanism in operation to circulate refrigerant through the evaporator means, said maintaining switch remaining closed as long as either maintaining circuit is completed.

21. In a refrigerating apparatus having evaporator means for controlling the condition of a medium and an electrically controlled mechanism for controlling the circulation of refrigerant through the evaporator means, the combination of, switch means movable to on and off positions for controlling the electrically controlled mechanism, a control device responsive to a condition which is a measure of evaporator temperature, spring means for opposing operation of the control device, means controlled by the control device for moving the switch means to the on position to circulate refrigerant through the evaporator means when the evaporator temperature increases to a predetermined high value and to the off position to stop circulation of refrigerant through the evaporator means when the evaporator temperature decreases to a low value, and a control device responsive to the condition of the medium controlled by the evaporator means for regulating the spring means to cause the switch means to be opened at a lower evaporator temperature value when the condition of

the medium is above a desired value than when the condition of the medium is below the desired value.

22. In a refrigerating apparatus having evaporator means for controlling the condition of a medium and an electrically controlled mechanism for controlling the circulation of refrigerant through the evaporator means, the combination of, switch means movable to closed and open positions for controlling the electrically controlled mechanism, a control device responsive to a condition which is a measure of evaporator temperature for closing the switch means upon an increase in evaporator temperature and a pair of spring means opposing said control device for predetermined the evaporator temperature value at which the switch means is closed to circulate refrigerant through the evaporator means and for opening the switch means to stop circulation of refrigerant through the evaporator means when the evaporator temperature decreases, and a control device responsive to the condition of the medium controlled by the evaporator means for preventing one of the spring means from opening the switch means when the condition of the medium is above a desired value to cause the switch means to be opened at a lower evaporator temperature than when the condition of the medium is below the desired value and both spring means are effective to open the switch means.

23. In a refrigerating apparatus having evaporator means for controlling the condition of a medium and an electrically controlled mechanism for controlling the circulation of refrigerant through the evaporator means, the combination of, switch means movable to on and off positions for controlling the electrically controlled mechanism, a control device responsive to a condition which is a measure of evaporator temperature, spring means for opposing operation of the control device, means controlled by the control device for moving the switch means to the on position to circulate refrigerant through the evaporator means when the evaporator temperature increases to a predetermined high value and to the off position to stop circulation of refrigerant through the evaporator means when the evaporator temperature decreases to a low value, a control device responsive to the condition of the medium controlled by the evaporator means for regulating the spring means to cause the switch means to be opened at a lower evaporator temperature value when the condition of the medium is above a desired value than when the condition of the medium is below the desired value, and a control device responsive to the pressure on the high pressure side of the refrigerating apparatus for moving the switch means to the off position whenever the pressure increases to a predetermined high value.

24. In a control device, in combination, a control member movable to first and second operative positions for performing a control function, first and second spring means urging said member toward said first position, automatic means for moving said member in opposition to said spring means to said second position, control means cooperative with one of said spring means in a manner to render it ineffective to urge said member towards said first position and automatic means for operating said control means.
